Patented Aug. 13, 1918.

UNITED STATES PATENT OFFICE.

LOUIS PRICE, OF BROOKLYN, NEW YORK.

EXTENSION-LEG FOR COMPASSES.

1,275,741.

Specification of Letters Patent. Patented Aug. 13, 1918.

Application filed August 2, 1917. Serial No. 184,079.

To all whom it may concern:

Be it known that I, LOUIS PRICE, a citizen of the United States, and a resident of Brooklyn, in the county of Kings and State 5 of New York, have invented a certain new and useful Improvement in Extension-Legs for Compasses, of which the following is a specification.

The present invention relates to drafting 10 instruments, and more particularly to an improved extension leg for use with compasses.

An object of the present invention is to provide an extension leg of such construction 15 that the same may be applied to an ordinary compass when it is desired to draw relatively large circles and the like, and when a beam compass is not at hand, and where the nature of the work precludes the 20 use of a beam compass; an extension leg which is longitudinally adjustable to adapt the ordinary compass for drawing circles and curves at various radii; an extension leg which is substantially the same size and appear- 25 ance as the ordinary extension leg; which may be economically manufactured; and which may be quickly and easily adjusted to the parts of the compass and also ad- justed for curves of various radii.

30 The above, and various other objects and advantages of this invention will be in part described, and in part understood, from the following detailed description of the present preferred embodiment, the same being 35 illustrated in the accompanying drawing wherein:

Figure 1 is a side elevation of an ordinary compass having an extension leg constructed according to the present invention 40 applied thereto, and being partly extended.

Fig. 2 is a detail perspective view, partly broken away, of one of the sliding sections of the extension leg.

Fig. 3 is an edge view of the extension 45 leg of this invention collapsed or folded.

Fig. 4 is a transverse section taken substantially on the line 4-4 of Fig. 3, being enlarged and looking in the direction indicated by the arrows.

50 Fig. 5 is a transverse section through the body portion of the extension leg with the slides removed therefrom.

Fig. 6 is a transverse section through one of the slides employed.

55 Fig. 7 is a transverse section through a

modified form of extension leg constructed according to the present invention.

Referring to this drawing, A and B designate the legs of an ordinary compass which are pivotally connected together at their upper ends in the yoke C. The leg A is provided in the usual manner with the anchoring section D, and the leg B is provided upon its lower end with a socket E into which is detachably fitted the stem F of the usual scribe leg G. As shown, the anchoring sections or legs B and G are provided at their upper ends with hinge joints by means of which the sections D and G may be adjusted in substantially parallel 70 relation irrespective of the angle between the legs A and B.

The extension leg of this invention comprises a bar or body part 10 having openings 11 and 12 in the opposite sides thereof which may be of dove-tail form, as shown in Fig. 5, or which may be rectangular, as shown in Fig. 7. These openings 11 and 12, or their substantial equivalent, form guides at the opposite sides of the bar 10 which 80 extend longitudinally thereof, and preferably throughout the entire length of the bar.

The bar 10 carries in the guides 11 and 12 a pair of slides 13 and 14. These slides 13 and 14 are in the form of relatively thin 85 bars which correspond in form at their opposite longitudinal edges to the guides 11 and 12 for the purpose of retaining the bars in longitudinal alinement with the body bar 10, and in the form shown in Figs. 5 and 6, 90 for retaining the slides 13 and 14 from displacement from the opposite sides of the body bar 10. The slides 13 and 14 are adapted to move longitudinally in the guides 11 and 12, and for the purpose of securing 95 the slides in adjusted positions, the body bar 10 is provided near its opposite lateral edges with thumb screws 15 threaded through preferably one side of the bar 10, and which are adapted to bind against the adjacent 100 edge portions of the slides 13 and 14.

The slide 13 is provided upon one end with a head 16 in the form of a flat plate adapted to lie against the adjacent end of the body bar 10, and preferably conforming 105 to the cross-sectional shape and size of the body bar. The head 16 is provided with an attaching stem 17 projecting longitudinally from the head and adapted to engage in the socket E of the leg B. The slide 14 is pro- 110

vided upon its opposite end portion with a head 18 which is preferably in the form of a socket corresponding to the socket E of the compass, and which is adapted to receive 5 therein the stem F of the scribe section G. The head 18 is adapted to be located at the lower or outer ends of the extension leg, and is preferably provided with a knob 19 projecting outwardly from the head 18 and 10 adapted to be grasped in the fingers for turning the scribe section G and the latter is secured to the leg extension. This knob 19 is also adapted to be used in sliding the section 14 in the body bar 10, and in also sliding 15 the body bar 10 upon the section 13, which latter is adapted to be secured and anchored to the leg B of the compass.

The body bar B is preferably provided, at least upon one side, with a longitudinal row 20 of graduations 20 by means of which certain predetermined positions of adjustment of the slides 13 and 14 may be found.

The graduations or scale 20 admit of the forming of arcs on radii of different relative lengths. When the compass is used 25 with the extension leg of this invention applied thereto, the extension leg is disposed horizontally with the members D and G extending vertically. The extension leg is 30 first adjusted without reference to the scale 20 unless the scale 20 is proportioned according to the distances between the members D and G. After the arc or circle is drawn, the extension leg may then be adjusted by using 35 the scale 20 to move the members B and G toward or from each other to form a circle or arc on a radius which is either smaller or larger than the one first formed. The scale 20 is preferably divided into standard unit 40 of measurements and fractions thereof, such as inches, and by such means the relative length of the arc may be quickly and accurately found.

In the modified form shown in Fig. 7, the 45 body bar 10^a has guide slots in its opposite sides of rectangular form adapted to receive the slides 13^a and 14^a of corresponding cross-sectional form.

In the use of the improved extension leg, 50 it is only necessary to remove the scribe section G of the compass and insert the stem 17 of the extension leg in the socket E. The slide 13 is thus secured to the leg B of the compass, and by loosening the adjacent set 55 screws 15, the body bar 10 may be moved longitudinally upon the slide 13 into the desired position. This position may be determined by the scale of graduations 20. As soon as the adjustment is had, the other set 60 screw 15 may be loosened and the slide 14 extended from the body bar 10, as shown in Fig. 1. The set screws 15 are of course tightened as soon as the desired adjustment of the slides 13 and 14 is obtained. The 65 scribe section G is now secured by means

of its stem F in the socket head 18 of the lower slide 14. In use, the knob 19 may be grasped in the fingers and the parts moved into the various desired positions of adjustment, and the knob 19 may be employed for 70 swinging the scribe section G in the operation of drawing an arc, circle or the like.

It is of course understood that various changes and modifications may be made in the details of construction and design of the 75 above specifically described parts of this invention without departing from the spirit thereof, such changes and modifications being restricted only by the scope of the following claims.

I claim:—

1. In an extension leg for compasses, the combination with a leg, and a removable scribe section for the leg, of a pair of slidably connected members, means for securing the members in various positions of extension, means for attaching one of said members to said leg in lieu of the scribe section, and means for securing the other member to the scribe section.

2. In an extension leg for compasses, the combination with a leg, and a removable scribe section for the leg, of a pair of slidably connected members, means for securing the members in various positions of extension, a head mounted on one of said members adapted to interchangeably engage said leg, and a head mounted upon the opposite member adapted to interchangeably engage 95 said scribe section.

3. In an extension leg for compasses, the combination with a leg, and a removable scribe section for the leg, of a body bar having guides on its opposite sides, slides adjustably mounted in said guides and adapted to be extended from the opposite ends of the body bar, means for securing said slides in various positions of extension, an attaching means carried upon the opposite outer ends of said slides adapted for 100 detachable engagement with said leg and said scribe section.

4. In an extension leg for compasses, the combination with a leg, and a removable scribe section for the leg, of an elongated body bar provided with recesses extending longitudinally in the opposite sides thereof, slides mounted in the recesses of the body bar and adapted to extend longitudinally from the opposite ends thereof, means for binding said slides in the recesses to hold the slides in adjusted position, and heads mounted upon the opposite outer ends of said slides adapted for detachable engagement with said leg and said scribe section 115 respectively.

5. In an extension leg for compasses, the combination with a leg, and a removable scribe section for the leg, of a body bar substantially rectangular in cross-section 120

and provided with longitudinal extending dove-tailed grooves in the opposite sides thereof, a pair of slides of dove-tail cross-section fitting in said grooves and adapted 5 to be adjusted longitudinally through the bar and extending beyond the opposite ends thereof, set screws threaded in one side of the bar adapted to engage the adjacent edge portion of said slides to bind the latter in 10 adjusted position, and attaching heads mounted upon the opposite outer ends of said slides adapted for engagement respectively with said leg and said scribe section.

6. In an extension leg for compasses, the 15 combination with a leg, and a removable

scriber section therefor, of a body bar provided in opposite sides with guiding recesses extending longitudinally of the bar, a pair of slides fitting in said recesses and adapted to be extended from the opposite 20 ends of the bar, a scale on the bar coöperating with the slides to determine the positions of adjustments thereof, means carried by the body bar for securing the slides when adjusted, and attaching means carried upon the opposite outer ends of said bar for engagement respectively with said leg and said scribe section. 25

LOUIS PRICE.
